UNITED STATES PATENT OFFICE

ALBERT O. BUCKIUS, OF CLEVELAND, OHIO, ASSIGNOR TO NATIONAL MALLEABLE AND STEEL CASTINGS COMPANY, OF CLEVELAND, OHIO, A CORPORATION OF OHIO

JOURNAL BOX

Application filed August 12, 1927, Serial No. 212,446. Renewed July 11, 1931.

My invention relates to journal boxes, and particularly to journal boxes of the roller bearing type intended for use on freight car trucks. It is customary in journal boxes used in freight car service to attach the boxes rigidly to the car side frames and to provide for the required flexibility between the box and the axle itself by crowning the journal wedge in a direction transverse to the car and allowing a certain amount of clearance between the sides of the wedge and the box, so as to provide limited movements in both vertical and horizontal planes within the box.

When, however, roller bearings are used it is not practical to provide the necessary flexibility between axle and journal box without unduly increasing the size and weight of the box. Hence I have so constructed my journal boxes and the co-operating parts of the side frame to permit the necessary flexibility between these parts by providing radial surfaces about which the parts may move both horizontally and vertically relative to each other.

My invention also comprises various features which I shall hereinafter describe and claim.

In the accompanying drawings, Fig. 1 is a plan of a portion of a side frame with a journal box assembled therein embodying my invention; Fig. 2 is a side elevation thereof; Fig. 3 is an end elevation thereof; Fig. 4 is a plan similar to Fig. 1 but with the frame and box in the position they would assume when rounding a curve in the direction indicated by the arrow; and Figs. 5, 6, 7 and 8 are transverse sections showing modified forms of top lugs.

Referring more specifically to the drawings, the side frame A is provided with depending jaws 2 and 3, the inwardly facing parts of which are of channel shape so as to provide recesses 4 therein, as is indicated in Fig. 1, to receive the side lugs 5 of the journal box B. At the top of the opening between the jaws 2 and 3 the frame has a recess 6 to receive a lug 7 formed on the top of the journal box B. Pins 8 are inserted through registering apertures 9 in the jaws 2 and 3

below the lugs 5 to prevent separation of the box from the side frame in case of derailment or during handling of the truck when disassembled from the car body. The pins may be held in position by the cotters 10.

To provide for the lateral movement of the frame A relative to the box B I have formed the surfaces 11 on the lugs 5, which bear against the surfaces 12 on the frame on radii struck from the intersection of the center lines of box and frame, so that when the box is angled horizontally with respect to the frame there will be a full bearing contact between box and side frame on a pair of these surfaces. It will therefore be seen that when one side frame advances slightly ahead of the other, as when the car is rounding a curve, a full area of contact will be maintained between box and frame upon a pair of these surfaces, as is shown in Fig. 4. This is of particular importance when brakes are applied, and the momentum of the car thrusts forwardly against the axle, carrying the side frame against the journal box with great force.

The vertical bearing faces 16 at the sides of the top lug 7 and the corresponding surfaces 14 are also formed on equal radii so as to provide a full contact between a pair of such surfaces when box and frame are also angled in a horizontal plane. These surfaces 16 and 14 also serve to limit the transverse movement of the box with respect to the side frame, and hence clearance is provided at the sides 15 of the lugs 5 and ends 13 of the lug 7 to avoid contact of such surfaces with the side frame under normal conditions.

To provide for vertical angling the top surface 17 of the lug 7 may be formed on a radius so that the box may move relative to the flat bearing surface 18 by which the box B supports the side frame A, as is shown in Fig. 3.

In Figs. 5, 6, 7 and 8 I have shown the top portion of the journal box formed of a separate member. In Fig. 5 the separate member 20 seats over an upward projection 21 on the box and has an arc shaped upper surface 22 which engages a flat surface 23 on the side frame. In Fig. 6 the upper surface 24 of the

separate member is flat, while the corresponding surface 25 on the frame is arc shaped. In Fig. 7 the separate member 26 is secured to the side frame by a projection 27 held in a slot 28 by a pin 29. Here the top surface 30 of the box is arc shaped and cooperates with the flat under surface 31 of the separate member. In Fig. 8 the top surface 32 of the box is flat while the bottom 33 of the separate member is arc-shaped.

10 The purpose of employing a separate piece as shown in Figs. 5, 6, 7 and 8 is to relieve the journal box and the side frame of wear. The wear is taken on separable pieces which 15 can be replaced or which can be made hard enough to withstand wear.

15 The terms and expressions which I have employed are used as terms of description and not of limitation, and I have no intention, in the use of such terms and expressions, of excluding any mechanical equivalents of the features shown and described, or portions thereof, but recognize that various structural modifications are possible 25 within the scope of the invention claimed.

What I claim is:

1. The combination of a journal box having side and top projections thereon, with a side frame having recesses into which said 20 projections fit, means for retaining the box in the frame engaging the side projections, the top projection providing the supporting bearing for the side frame and the ends of the side projections co-operating at times 25 with vertically disposed walls of the recesses in the side frame.

2. The combination of a journal box and a side frame, the box and frame having complementary arc shaped surfaces to permit 40 lateral angling between box and frame, the said box and frame having also dissimilar engaging surfaces to permit vertical angling.

3. The combination of a journal box and a side frame, the box having arc-shaped surfaces substantially at right angles to each 45 other cooperating with similarly shaped surfaces on the frame, the cooperating surfaces being spaced apart to allow limited lateral movement between the box and the frame.

50 4. A journal box and side frame connection in which cooperating curved surfaces are formed on the box and frame to provide angular flexibility therebetween, said cooperating surfaces being spaced apart to also provide for lateral movement therebetween.

5. The combination of a journal box and a side frame, the box having projections at the sides and top provided with arc-shaped 60 surfaces for engagement with cooperating surfaces on the frame, a clearance being provided between the corresponding surfaces of the box and frame, the arc-shaped surfaces of the side journal box projections limiting the relative movement of the box and frame 65 in one direction and the arc-shaped surfaces

of the top journal box projection limiting the relative movement of the box and frame in another direction.

6. The combination of a journal box and a side frame, the box having projections at the sides extending into recesses in the frame, the projections and recesses having a substantial clearance therebetween to allow both angular movement and bodily lateral movement between the journal box and side frame. 75

7. The combination of a journal box and a side frame, the box having projections at the sides and top provided with arc-shaped surfaces for engagement with cooperating surfaces on the frame, the corresponding surfaces of the box and frame having a substantial clearance therebetween, the arc-shaped surfaces at the top of the box being formed on radii substantially greater than the distance between them, thereby producing relatively flat surfaces which will allow relative movement between the box and frame in a direction to bring the arc-shaped surfaces of the side journal box projections into engagement with the side frame while maintaining 80 an area of contact between one of said relatively flat surfaces with the side frame.

8. The combination of a journal box and side frame, said side frame having depending jaws provided with vertically extending curved surfaces for the reception of a journal box therebetween, said journal box having on its sides curved surfaces for co-operation with said jaw surfaces to provide horizontal angular flexibility therebetween, said side frame and top of said box having co-operating surfaces one of which is curved longitudinally of said box and straight transversely thereof whereby said box is held against axial rotation but is free to angle horizontally and 95 vertically relative to said side frame. 100

9. The combination of a journal box and a side frame, the box having vertical arc-shaped surfaces substantially at right angles to each other cooperating with surfaces on the frame to permit lateral angling between the box and frame, the cooperating surfaces being spaced apart to allow limited bodily lateral movement between the box and the frame. 110

DISCLAIMER

1,828,312.—*Albert O. Buckius*, Cleveland, Ohio. JOURNAL BOX. Patent dated October 20, 1931. Disclaimer filed March 20, 1933, by the assignee, *National Malleable and Steel Castings Company*.

Hereby disclaim from the scope of claims 2, 4, and 8 of said Letters Patent any constructions other than those in which the complementary arc-shaped surfaces on the journal box and side frame are concave toward the vertical axis of the journal box.
